MINIATURE CALENDAR

Charles Kahn, Brooklyn, N. Y.

Application October 19, 1933, Serial No. 694,223

6 Claims. (Cl. 40—108)

This invention relates to new and useful improvements in a miniature calendar for the caps of fountain pens, pencils and the like.

The invention has for an object the construction of a miniature calendar which is characterized by a body adapted to be inserted within the cap and arranged with a web support exposed for viewing and the provision of a calendar web extended over said web support and associated with a mechanism by which the calendar may be adjusted.

Still further, the invention proposes a pair of spaced rollers within the body supporting said calendar in a manner that it may be easily moved forwards and rearwards.

As another object of this invention a simple novel arrangement is exposed for actuating said rollers so as to adjust the calendar as previously mentioned.

As another object of this invention it is proposed to provide a knob for location on the end of the cap and constituting a knob for operating the calendar.

The invention also proposes the arranging of the calendar upon the web strip in a manner so that the months are arranged, adjacent each other, and each of the months divided off into the days as is customary construction.

As another object of this invention an arrangement is proposed whereby the body is conveniently removably held within the cap.

Still further the invention contemplates a device as mentioned which is simple and durable in construction and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a fountain pen cap constructed according to this invention.

Fig. 2 is an enlarged vertical sectional view of Fig. 1.

Fig. 3 is a sectional view taken on the line 3—3 of Fig. 2.

Fig. 4 is a horizontal sectional view taken on the line 4—4 of Fig. 2.

Fig. 5 is a perspective view of a calendar body removed.

Fig. 6 is a vertical sectional view of the knob of the device.

Fig. 7 is a fragmentary sectional view showing a portion of the inner wall of the cap to illustrate a certain part.

Fig. 8 is a fragmentary elevational view of the calendar web.

Fig. 9 is a fragmentary view similar to a portion of Fig. 2 but illustrating a modified arrangement.

Fig. 10 is a horizontal sectional view taken on the line 10—10 of Fig. 9.

Fig. 11 is a fragmentary enlarged detailed sectional view showing the engagement of one of the pegs of a knob of the device with the body of the calendar of the device.

Fig. 12 is a side elevational view of a pencil with a cap constructed according to this invention.

The miniature calendar, according to this invention, is associated with a cap 10 having a side window 11 and an opening 12 extended in from one end. A body is inserted into the open end of the cap and has a web support 13 located immediately behind the window opening 11. A calendar web 14 is extended over the web support 13 and is wound upon rollers 15 and 16 mounted within the body. A means is provided for winding the web from one to the other of the rollers to expose different portions of the web through the window, and this means includes a knob 17 for its operation, said knob also covering the open end of the cap 10. The upper end of the cap 10 has a slightly reduced portion 10^a extending slightly into the knob for avoiding a space between these parts.

The window 11 is closed by a piece of transparent material 18. The window 11 is surrounded by recessed sides 11' into which the edges of the transparent material 18 engage. The recess 11' serves to removably hold the transparent material. This arrangement allows removal of the transparent material so that access may be had to the interior of the cap 10 for the purpose of removing the calendar or adjusting the calendar or other similar reasons. The cap 10 is shown provided with a regular clip 19. The bottom side of the cap is open so as to be engageable upon a fountain pen according to conventional practice. The body, which is engaged into the opening 12, comprises several horizontal discs, illustrated as three in all, indicated by reference numerals 20, 21 and 22 arranged superimposed with the disc 20 at the bottom and a disc 22 at the top. A continuation 23 of smaller width connects one side of the disc 22 with the disc 21. The web support 13 connects the discs 20 and 21.

Fig. 1 is a side elevational view of a fountain pen cap constructed according to this invention.

Fig. 2 is an enlarged vertical sectional view of Fig. 1.

Fig. 3 is a sectional view taken on the line 3—3 of Fig. 2.

Fig. 4 is a horizontal sectional view taken on the line 4—4 of Fig. 2.

Fig. 5 is a perspective view of a calendar body removed.

Fig. 6 is a vertical sectional view of the knob of the device.

Other supports, strips 24, extend between the discs 20, 21 and 22 and hold these discs as a unit. The rollers 15 and 16 are fixed upon vertical shafts 25 rotatively engaged through the discs 20, 5 21 and 22 and arranged with similar crank portions 26 located in the space between the discs 21 and 22. A central shaft 27 is also rotatively mounted through the discs 20, 21 and 22 and also has a crank portion 26 similar to the crank portions 26 previously mentioned and also located 10 in the space between the discs 21 and 22.

A bar 28 connects all of the cranks 26 together to cause them to rotate in unison. The cranks engage through openings in the bar 28 so as to be turnable therein. The knob 17 is mounted upon the upper end of the shaft 27 which is extended above the disc 22. The shafts 25 terminate at the disc 21.

The upper end of the shaft 27 is formed with 20 a square head 29 which slidably engages in a similar shaped opening 30 arranged upon the knob 17. Springs 31 and 31' are interposed in the opening 30 and act between the base and top of the opening 30 and the head 29 so as to normally hold the knob in a neutral intermediate 25 position. A plug 32 closes the bottom of the opening 30, and the upper end of the shaft 27 slidably passes through this plug. Several pegs 33 project from the bottom of the knob 17 and 30 have rounded bottom ends normally slightly engaged into openings 34 in the top disc 21. The normal position of the pegs is illustrated in Fig. 11. The arrangement is such that when the knob 17 is turned the pegs 33 can ride out of the 35 apertures 34 which are arranged close together and in a circle as illustrated in Fig. 3 and so hold the knob 17 in various adjusted positions. The spring 31 serves to resiliently urge the knob 17 downwards so as to cause the engagement of the 40 pegs 33 into the top portions of the openings 34. If desired the knob 17 may be depressed against the action of the spring 31' so as to extend the pegs 33 sufficiently deep into the openings 34 to 45 connect the knob and the disc for turning the body of the calendar.

A finger 35 projects from the periphery of the bottom disc 20 and engages in a longitudinal slot 36 former upon the inner wall of the cap and extending from the open end downwards to a 50 small slight branch slot 37 located at the point so that when the finger 35 engages therein the top disc 22 will be substantially flush with the top of the cap. An expansion spring 38 is interposed between the bottom disc 20 and a plug 39 fixed 55 within the cap.

Each of the rollers 15 have cores 40 with projecting prongs or hooks 41 adapted to engage 60 openings in the ends of the web for the attachment of the web upon the cores. The web 14 is illustrated with some degree of detail in Fig. 8 showing the arrangement of the calendar in the window opening 11 of a size to completely expose 65 one month upon the web.

The operation of the device consists in turning 65 the knob 17 in one direction or the other to similarly move the web to expose different portions. As the knob 17 is turned the shaft 27 will turn correspondingly and the bar 28 will transmit this motion to the cranks 26 to rotate the rollers 15 70 and 16 to unwind the web from one of the rollers to the other. The calendar web may be changed by removing the transparent material 18 and reaching the web through the opening 12. The calendar web may also be changed by removing 75 the entire body. To do this, it is necessary that

the knob 17 be first depressed to engage the pegs 33 into the openings 34. Then the body should be slightly turned so as to disengage the finger 35 from the portion 37 of the groove in the inner wall of the cap. The slight turn presses the 5 finger 35 with the groove 36 and then the spring 38 slightly ejects the body. The body may next be lifted out completely from the cap. The knob 17 may then be turned in one direction until the web is completely wound upon one roller only 10 and the end disengaged from the core of the other roller.

In Figs. 9 to 11 a modification of the invention has been disclosed which distinguishes from the previous form merely in the manner in which 15 rotations are transmitted to the rollers. More particularly, a central gear 45 is fixed upon the central shaft 27 and meshes with gears 46 upon the shafts 25 of the rollers. In other respects this form is similar to the previous form, the 20 same parts may be recognized by the same reference numerals. When the knob 17 is turned the shaft 27 will also be moved and the gear 45 will simultaneously turn the gears 46 in one direction or the other as desired. 25

In Fig. 12 another variation of the invention has been disclosed in which a cap 10' is engaged upon a pencil 48. This cap is shown with a reduced bottom portion 49 to engage upon the end of the pencil which is of smaller diameter compared with the main portion of the cap 10. In other respects the form of the invention is identical to that previously described and similar parts may be recognized by corresponding reference numerals. 30

While I have shown and described the preferred embodiment of my invention, it is to be understood that I do not limit myself to the precise construction herein disclosed and the right is reserved to all changes and modifications coming within the scope of the invention as defined in the appended claims. 35

Having thus described my invention, what I claim as new and desire to secure by United States Letters Patent is:— 40

1. In combination with a cap having a side window and open at one end, a body inserted within the open end and having a web support behind said window, a pair of spaced rollers in said body, a calendar web extended over said web support and wound upon said rollers, and means for winding the web from one to the other of the rollers to expose different portions through the window comprising shafts connected with said rollers and having crank portions, a bar connecting said crank portions, and means for moving said bar to turn said shafts in unison. 45

2. In combination with a cap having a side window and open at one end, a body inserted within the open end and having a web support behind said window, a pair of spaced rollers in said body, a calendar web extended over said web support and wound upon said rollers, and means for winding the web from one to the other of the rollers to expose different portions through the window, shafts connected with said rollers and having crank portions, a bar connecting said crank portions, and means for moving said bar to turn said shafts in unison, comprising a crank connected with said bar and a knob for turning 55 said latter mentioned crank. 60

3. In combination with a cap having a side window and open at one end, a body inserted within the open end and having a web support behind said window, a pair of spaced rollers in 70

- 5 said body, a calendar web extended over said web support and wound upon said rollers, and means on said body for winding the web from one to the other of the rollers to expose different portions through the window, and a finger from said body engaging in a longitudinal groove in said cap and extendible in a short transverse groove in the cap in a fully inserted position of the body within the opening in said cap. 5
- 10 4. In combination with a cap having a side window and open at one end, a body inserted within the open end and having a web support behind said window, a pair of spaced rollers in said body, a calendar web extended over said web support and wound upon said rollers, and means for winding the web from one to the other of the rollers to expose different portions through the window, comprising a shaft rotatively mounted on said body and connected with said knob, other shafts connected with said rollers, and a connecting bar connecting crank portions formed upon said shafts. 10
- 15 5. In combination with a cap having a side window and open at one end, a body inserted within the open end and having a web support behind said window, a pair of spaced rollers in said body, a calendar web extended over said web support and wound upon said rollers, and means for winding the web from one to the other of the rollers to expose different portions through the window, said body comprising several horizontal discs spaced from each other and held in fixed positions with connector strips, said pair of rollers 15 being mounted between certain of said discs, one of said discs being formed with a peripheral finger engageable through a longitudinal groove upon the inner wall of said cap and extendible into a short transverse groove in the fully inserted position of the body within the opening in the cap, and resilient means interposed between said body and cap for normally tending to slightly extend the body. 20
